UNITED STATES PATENT OFFICE.

LUDWIG WALLSTROM, OF LIMA, PERU.

BURNER.

Application filed July 28, 1925. Serial No. 46,634, and in Peru April 8, 1925.

My invention relates to burners, of the type employing oil for fuel, and in which, if desired, a gas such as oxygen, or a pulverulent solid fuel may be used in addition to the liquid fuel. The purpose of the invention, generally stated, is to provide a burner in which it is possible to effect a nicer adjustment than has been possible heretofore, so as to obtain, under readily controllable conditions, the highest value of combustion from the oils, and a flame of whatever length may be desired. The burner is particularly designed for use in producing steam and for heating purposes either on shipboard or land, besides for metallurgic and calcination purposes.

My invention resides in the characteristics, constructions and combinations of elements indicated in the appendant claims.

20 In the accompanying drawings:—

Figure 1 is a longitudinal section of an oil burner constructed in accordance with my invention.

25 Figure 2 and 4 are a fragmentary longitudinal section of a modified form of the same burner.

Figure 3 is an enlarged sectional view of the rear portion of Fig. 1, showing how a valve stem is positioned.

30 Figs. 5 and 6 are fragmentary elevations, partly in section, of the ends of burner tubes in which no valve stems are provided.

Fig. 7 is a section partly in elevation through a cam and associated mechanism of Fig. 4 for shifting the burner tubes.

Referring to Figures 1 and 3, the casing for the burner comprises an elbow 1 into which is threaded a sleeve 2. The latter is connected to the nozzle 3, by means of clamping bolts and interposed, spacing rings 4, whereby the length of the nozzle may be varied. A stationary air conduit 5 leads to the lower opening in elbow 1. The burner may be, and preferably is, supported by means of the stationary conduit. Air is supplied by a simple ventilator or fan, standing at a pressure of from 6 to 10 inches of water.

Two telescoping tubes 6 and 7 extend centrally through the nozzle and the horizontal turn of the elbow, and pass through the rear vertical wall of the latter. The annular space between the outer tube 6 and the inner tube 7 constitutes a fuel passageway. Within the tube 7 is a rod 8 which carries at one end a valve 9. A plate 10 is se-

cured to the end of tube 7 and provides two valve seats 11 and 12, the former cooperating with valve 9 and the latter with a sleeve 13 secured to tube 6. A ring 14 having an inner conical surface 15 surrounds the atomizer or plate 10, and is held slightly spaced from the inner wall of nozzle 3 by supporting pins 16, preferably three in number.

An interiorly threaded bushing 17 receiving pipe sections 18 and 19 is clamped in an opening in the sleeve 2, the joints being properly packed as shown. The upper end of pipe section 19 is received in the four-way joint 20, through which extend the tubes 6 and 7 and the valve stem 8. The outer tube is adapted to slide through the joint 20 as will be described presently, and packing is provided between it and the tube. Further on tube 6 is provided with slots, and one of these serves as registering slot through which passes a pin 21 secured to the joint. In this way, rotation of the tube 6 is prevented, while axial reciprocation of the tubes and stem is possible to an extent corresponding to the length of the slots through which the pin 21 extends. The connection 19 between the sleeve 2 and the joint maintains the tubes in place and substantially prevents wobbling of the atomizer 10 within the ring 14.

The tube 6 is provided with a slot or slots 22 in addition to those receiving the pin 21, to facilitate the commingling of oil, and air if operation is stopped, oil being supplied, under a simple gravity pressure at a height of 10 to 16 feet maximum through a pipe 23 and the pipe sections 19 and 18, the latter containing a strainer 24.

Opposite the connection between the joint 20 and section 19, an elbow 25 is screwed into the joint. This elbow contains a cock 26, which is turned off during operation of the burner. When such operation is stopped the cock may be opened so as to blow air into the joint and the tubes to clear the latter of residue. Access to the cock is had through an opening in the top of sleeve 2, through which a tool may be inserted. During operation, said opening is closed by a cap 27.

A peep hole is provided at the rear of elbow 1 and is adapted to be closed by a plug 28.

An opening is formed in the rear vertical wall of elbow 1 and the tubes 6, 7 and stem 8 pass therethrough, the tube 6 being exteriorly threaded some distance on each side

of the opening. The outer wall of the elbow around the opening is recessed and receives the hub 29 of a hand wheel 30 which is interiorly threaded to engage the threads on tube 6. The hub 29 has a peripheral groove 31 receiving the semicircular edge of a plate 32 fastened to the wall of the elbow, so that by turning the wheel 30, the tube 6 (and with it the tube 7 and stem 8, as will be explained) will be axially shifted, said wheel being held against axial movement by the elbow and the plate 32.

A sleeve 33 is threaded on the end of tube 6 and firmly secured in place, as by means of a set screw. This sleeve may be provided with two scales, which may be engraved on the sleeve itself or provided on a plate or plates secured to the sleeve. One scale is numbered from 0 to 7; the other from 7 to 0. In line with each numeral of the scale, I preferably provide a groove or ridge encircling the sleeve (see Fig. 2). The grip portion of the hand wheel 30 has a number of radial, inwardly directed pointers 34 to cooperate with the scales or grooves on sleeve 33. As the wheel is turned, the tube 6 and sleeve 33 are moved backward or forward, and the location of the tube is indicated by the pointers and the scale 30 which is being used.

The sleeve 33 has, at the end of tube 6, an inner flange, nicely fitting around the inner tube 7, and between which and the end of tube 6 I provide packing 35. The rear part of the sleeve is enlarged and interiorly threaded to receive a gland 36, holding in place additional packing for the tubes.

The rear end of tube 7 is threaded and receives a nut 36' having a peripheral groove and locked in place by a jam nut 37. A diametrically split ring 38 fits into said groove and is fastened to the hub of a handle 39. The hub is threaded on the extreme end of sleeve 33, so that by turning handle 39, the inner tube is shifted relatively to the outer tube. The sleeve 33 has a flange 40 whose surface is notched and engaged by a spring catch 41 secured to the handle, whereby the latter may be latched in any desired position of adjustment. I prefer to provide numerals beside the notches on flange 40, to indicate the relative position of tubes 6 and 7 and consequently the micrometrical extent of opening of valve 12 for the supply of oil.

A joint 42 is screwed on the extreme end of tube 7 and has a nipple 43 to receive a hose or other flexible conduit communicating with a source of air under pressure. The valve stem 8 is packed by a gland 44 in the joint, and the extreme end of the stem is threaded. A wheel 45 is threaded on the end of the joint and carries a retaining pin 46, which bears on the surface of the joint 42. Said wheel has an inner flange 47 while the threaded end of the valve stem re-

ceives a flanged sleeve 48. Between flange 47 and the flanged end of sleeve 48 a spring 49 is interposed, tending to force valve 9 against its seat 11. The expansion of the spring and rearward movement of the valve stem are, however, limited by a diametrically split ring 50 secured to handwheel 45. A nut 51 having a flange 52 locks the sleeve 48 in place. The flange 52 fits into a circumferential groove in the split ring 50. In assembling the parts, the spring 49 is first inserted inside wheel 45, about the valve stem. Then sleeve 48 is screwed on until the spring forces valve 9 against its seat. Next, the nut 51 is threaded on the end of the valve stem until it jams against sleeve 48. Finally, the valve stem is pressed inwardly and the halves of ring 50 are secured into place by being screwed onto wheel 45, with the flange 52 fitting into the groove in the ring. The parts are so adjusted that the sleeve 48 engages the front face of ring 50 while the flange 52 engages the rear wall of its groove. The latter is so much wider than the flange 52 that the valve stem is permitted a little axial play against the action of spring 49. The clearance is illustrated in the enlarged showing of Fig. 3. I prefer to provide numerals beside the notches on the surface of the joint 42, to indicate how the valve 9 is adjusted relatively to the valve seat 11. Consequently the micrometrical extent of opening of flat valve 9, controls the supply of extra gases, which might be of oxygen alone, or combined with air, and injected in the center of the flame projected from the annular space between plate 10 and ring 14. In this way I avoid having to supply an excess of air to said annular space, and can, within reasonable limits, control the form and size of the flame. Referring now to the conical ring 14 and the atomizer 10, it is to be noted that the diameter of the latter is as great or almost as great as the smallest internal diameter of the ring. When the atomizer is at the extreme right, the largest annular opening is provided between the atomizer and the ring, and the scale 7 to 0 on sleeve 33 is used, the pointer 34 standing at 7. It is to be plainly understood that my invention is not limited to sizes or proportions, but I wish to set forth certain preferred measurements. The atomizer is 3 inches in diameter and the maximum clearance between it and the ring 14 is $\frac{5}{8}$ inch. The tube and valve stem can move through the joint 20 a maximum distance of $\frac{7}{8}$ inch. As shown in Fig. 1, the parts are set for a flame of the maximum length, say, with proper coordination of oil and air, about 4 feet. As the atomizer is retracted into the nozzle the flame shrinks to a minimum of say one foot. In adjusting the burner, the hand-wheel 30 is first turned until the

atomizer 10 is properly positioned, relative to the ring 14, as shown by the scale or scorings on sleeve 33. Then the handle 39 is turned to obtain an opening of proper size between the two tubes. Finally Figs. 4 and 6 show how the burner can dispense with hand-wheel 45 and valve stem 8, in this condition the tube 7 is now empty, for a supply of air alone, or combined, if desired, with different solid fuels in pulverulent form which may be injected with the air through joint 42 or nipple-nut 57 (Fig. 6), and air through the nipple 58; the opening 59 serves for cleaning, etc. But the latter operation with solid fuels may not be for firing purposes.

In the modified structure shown in Fig. 4, the burner is designed to produce a flame which, at its shortest, is about as long as the shortest flame produced by the burner of Fig. 1, but which may have a maximum length in this case of 8 feet or more.

In Figure 2, the ring 14 is smaller than the ring in Fig. 1, and the atomizer is of only about two-thirds the diameter of the atomizer in Fig. 1. Between the ring 14 and the inner wall of the nozzle 3 a fixed ring 53 is provided, and the pins 16 are elongated to pass through said ring and engage the ring 14. The position of the latter is reversed relatively to Fig. 1, and the pointers 34 cooperate with the scale 0 to 7. The manner of relatively adjusting the two tubes is the same in Fig. 2 as in Fig. 1, but in Fig. 2 I have shown the valve stem 8 as provided with a needle valve 54 instead of the conical valve 9. Therefore the valve stem must be moved rearwardly to open the valve, instead of forwardly as in Fig. 1, and in consequence of this the sleeve 48 within the hand-wheel 45 is reversed in position, and the inner flange 47 of the hand-wheel is omitted, so that the rear end of the spring 49 bears against the ring 50 while its forward end bears against the flange on sleeve 48. Complete closing of the valve is prevented, as in Fig. 1, by the flange 52 on nut 51 cooperating with the groove in ring 50, but in Fig. 2 the spring 49 causes the flange 52 to bear against the forward wall of the groove in ring 50.

In Fig. 2 I provide for clearing out the tubes, after the burner ceases to operate, by means of steam. To this end, the upper opening of the joint 20 is connected with a pipe 55 passing through the sleeve 2, and closed by a cap 56 when the burner is in operation. This pipe may be connected with a steam inlet pipe when it is desired to clear out the tubes.

In the modified structure shown in Figs. 4 and 7, I dispense with the hand wheel 30 and provide means for extremely speedy shifting of the two tubes 6 and 7. An angle bracket 61 is bolted to the elbow 1, and pro-

vides a bearing 62 for vertical shaft which has an eccentric portion receiving an anti-friction cam ring 63. This ring is held in place between a lower shoulder 63^a on the shaft and its eccentric part and an upper plate 63^b secured to the shaft. The latter also has secured to it a spring 60 whose free end carries a pin adapted to travel in an arcuate slot on the horizontal surface of bracket 61. Numerals may be inscribed on the bracket beside the slot to indicate the adjusted position occupied by the tubes. A handle 66 is secured to the lower end of the shaft, to operate the cam 63, which projects between the shoulders 64^a of a sleeve 64, secured to the tube 6 in lieu of the sleeve 33 of Fig. 1. A bolt 67 depending from spring 60 passes through an arcuate slot in the bracket 61 and receives a nut 68, which, when tightened, locks the tubes in any desired position of adjustment.

The joint 42 on tube 7 may be used to supply air only, through nipple 69 and nut 70, or it may be used to supply air and also extra gases, the latter through a second nipple 75. Said nipple 75 is adapted to receive a gas-supply hose, and is preferably adapted to receive interiorly one of a number of steel plates. One of the plates may be imperforate so as to obstruct completely any passage through the nipple, and the others may have holes of varying diameters, so as to admit more or less gas under pressure. The opening 71 in the nipple is for observation and contains a glass.

And finally Fig. 5 shows a burner without employing the central rod 8, and which serves only for observation through a nut 72 provided with a glass.

I claim as my invention:

1. A burner comprising two telescoping, relatively adjustable tubes, affording a fuel passageway, a valve, a valve stem within the tubes for the valve, said stem being adjustable relatively of said tubes, a deflector plate detachably secured to one of the tubes and a cooperating ring having a conical inner surface surrounding the deflector plate.

2. A burner in accordance with claim 1, including a nozzle surrounding the ring, said ring being reversible in said nozzle.

3. A burner in accordance with claim 1 in which the deflector plate has a partly spherical rear surface.

4. A burner in accordance with claim 1, in which the deflector plate is mounted on the inner tube, providing a valve inlet between it and the outer tube.

5. A burner in accordance with claim 1, in which the valve stem is mounted for slight longitudinal play against the tension of a spring.

6. A burner comprising a casing having a nozzle, telescoping, relatively adjustable tubes extending through the casing to the

nozzle, a deflector plate supported on one of the tubes and adapted to cooperate with the nozzle, means for admitting fuel to the space between the tubes, said means being rigid with the casing and serving to support the tubes, a device for restraining the tubes from rotation while permitting them to move axially through such support, means for adjusting the plate and the tubes together axially of the nozzle, and independent means for relative axial adjustment of the tubes.

7. A burner in accordance with claim 6, in which the nozzle is adjustable longitudinally, and a ring is disposed in the nozzle, surrounding the forward ends of the tubes, the outer wall of the ring being spaced from inner wall of the nozzle.

8. A burner in accordance with claim 6, having means to admit a gaseous cleaning medium into the valve passageway in the tubes, the casing having an opening which is normally closed but adapted to be opened to render available the means for admitting the cleaning medium.

25 9. A burner in accordance with claim 1, in which the ring surrounding the atomizer has a minimum diameter approximately equal to the maximum diameter of the atomizer, whereby movement of the atomizer axially of the ring varies the extent of the clearance therebetween.

10. A burner comprising nested tubes affording fuel passageways and providing atomizing means at their outlet ends, a deflector plate supported by and surrounding the atomizing means, a cooperating ring having a conical inner surface surrounding the deflector plate, and means for adjusting at least one of the tubes with respect to said ring, said ring having a minimum diameter approximately equal to the maximum diameter of the deflector plate, whereby movement of the latter axially of the ring varies the extent of annular clearance therebetween.

11. A burner comprising nested tubes affording fuel passageways and providing atomizing means at their outlet ends, a deflector plate supported by and surrounding the atomizing means, a cooperating ring having a conical inner surface surrounding the deflector plate, and means for adjusting at least one of the tubes with respect to said ring, and a nozzle surrounding and supporting the ring, which is reversible in said nozzle and has an axial length substantially equal to the maximum distance through which the tubes are adjustable.

12. A burner comprising nested tubes affording fuel passageways and providing atomizing means at their outlet ends, a deflector plate supported by and surrounding the atomizing means, a cooperating ring having a conical inner surface surrounding the deflector plate, and means for adjusting at least one of the tubes with respect to said ring, said ring having a minimum diameter approximately equal to the maximum diameter of the deflector plate, whereby movement of the latter axially of the ring varies the extent of annular clearance therebetween.

13. A burner according to claim 6, having a ring provided with a conical inner surface cooperating with the deflector plate and mounted in the nozzle about the ends of the tubes, said ring being reversible in said nozzle and having an axial length substantially equal to the maximum distance through which the tubes are adjustable.

14. A burner according to claim 1, in which the valve is cone-shaped, and in which the deflector plate has a conical seat for the valve, the apex of the cone being directed against the direction of flow through the inner tube.

In testimony whereof I affix my signature.

LUDWIG WALLSTROM, Inc.
